UNITED STATES PATENT OFFICE.

HARRY L. ROBY, OF BARNESVILLE, OHIO.

BELT-ADJUSTING MECHANISM FOR TOBACCO BOOKING AND STRIPPING MACHINES.

1,283,309.

Specification of Letters Patent. Patented Oct. 29, 1918.

Application filed March 16, 1917, Serial No. 155,172. Renewed March 7, 1918. Serial No. 221,092.

To all whom it may concern:

Be it known that I, HARRY L. ROBY, a citizen of the United States, residing at Barnesville, in the county of Belmont and State of Ohio, have invented certain new and useful Improvements in Belt-Adjusting Mechanisms for Tobacco Booking and Stripping Machines, of which the following is a specification.

10 My invention relates to the improvements of belt adjusting mechanisms for tobacco stripping and booking machines and has particular relation to improved means for automatically holding the leaf carrying belts 15 taut or properly tensioned for effective work.

The objects of my invention are to provide a machine of the class specified with means whereby the usual belts which carry 20 the tobacco leaves over a central drum are automatically adjusted with reference to slack and tension;

To so construct and arrange my improved tensioning means as to prevent slipping 25 action of the belts and to compensate for the stretching strain which is ordinarily imposed on the belts during the operation of "booking" the tobacco leaves and by thus retaining the belts in proper contact with 30 the drum or the leaves forming the books;

To insure the pressing by the belts of the entire widths of the leaves and prevent the wrinkling of the leaves.

The preferred embodiment of my invention is shown in the accompanying sheet of drawings, in which similar characters of reference designate corresponding parts and in which—

Figure 1 is a rear view of a portion of 40 a tobacco stripping and booking machine showing my improved tensioning means applied to three belts thereof.

Fig. 2 is a section taken on line 2—2 of Fig. 1.

Fig. 3 is a detailed view in perspective showing the connection of the spring controlled arms with the rear shaft of the machine and

Fig. 4 is a diagrammatic view of the 50 course usually followed by one of the belts.

In machines of the particular class to which my invention relates, the tobacco leaves which are to be booked are fed into the front end of the same and on to a central and comparatively large drum which I 55 have outlined at "1" in Fig. 4. Through

the medium of a plurality of endless belts passing over said drum and over desirably arranged rollers which are mounted in a suitable framework of the machine, the 60 tobacco leaves are fed on to the drum and booked or piled one upon the other between the belts and the periphery of said drum.

The means however, of both booking and stripping the tobacco are well known and as 65 my invention relates only to the tensioning of the belts which are used, I have omitted from the drawings and specifications of this application a showing of the detailed construction of the machine. I have shown at 70 "3" however, two of the side frame members of the machine between which the drum and various guide rollers are mounted.

4 represents the leaf carrying belts which may be of any desired width and which may 75 be of any desired number, although but three of such belts are shown for the purpose of illustrating my invention. These belts running over suitably placed rollers such as those indicated at "5" and "6", each belt 80 leading from the roller "6" downward and rearward and over a pulley or idler "7" which is loosely mounted on the comparatively short horizontal arm or stub shaft "8" of a bell crank "9". The remaining arm 85 of said bell crank being rigidly connected or formed with a sleeve "10" which is rotatably mounted upon a transverse shaft "11" which is fixed between the frame members "3". It will be understood that there is 90 thus one of said sleeves "10" for each belt and for each of the pulleys.

Clamped in connection with each of the sleeves "10," preferably in the manner indicated at "12" in Figs. 2 and 3, is one end 95 of a rearwardly extending arm "13." "14" represents a yoke, the parallel arms of which have their ends affixed to the machine frame sides, said yoke being inclined downwardly and rearwardly as is shown more clearly in 100 Fig. 2 of the drawing. To the outer end of each of the arms "13" are hooked or otherwise suitably connected one or more coiled springs "15," there being two shown in the drawing. The lower ends of each pair 105 of springs "15" are connected with the head or upper end of a rod or bolt "16" which extends loosely through the lower member of yoke "14" and has its lower end portion threaded as indicated at "17." This threaded portion "17" of each of the rods or bolts "16" is adapted to receive an adjusting nut "18,"

- between which and the collar "19" arranged on the under side of the lower member of the yoke "14," is interposed a short coiled spring "20."
- 5 In machines of this class it has been customary to depend on manually movable weights carried on arms extending from the sleeves "10" but experience has proven that the regulation of the positions of such 10 weights is a difficult matter and one which required close attention in order to impart to the belts the proper degree of tautness. In many cases it has been found necessary after the belts have been in use for a period 15 of time to attach to these weights other heavy bodies for the purpose of taking up additional slack in the belts. By the construction of my device, it will readily be understood that all undesirable slack of the 20 belts is automatically taken up by the springs "15" and "20;" these springs being so constructed as to ordinarily impart to the arms "13" the desired downward pull and a consequent downward and outward pull on 25 the belts. However, in case it is desired to increase or decrease the degree of slack of the belts, it is obvious that this may be readily accomplished by turning upward or downward the adjusting nuts "18."
- 30 It will be understood that my improved tensioning means is such as to admit of its being readily connected with well known forms of tobacco stripping and booking machines.

Copies of this patent may be obtained for five cents each, by addressing the "Commissioner of Patents, Washington, D. C."

I claim:

1. In a belt adjusting mechanism for tobacco booking and stripping machines, the combination with a frame and endless belts mounted to travel therein, of a fixed shaft, sleeves rotatably mounted on said shaft, an arm extending from each of said sleeves, a belt pulley carried by each of said arms, a second arm extending from each of said sleeves, a frame bar, and springs adjustably connecting said frame bar and said second 45 named arms.

2. In a belt adjusting mechanism for tobacco booking and stripping machines, the combination with a frame and endless belts mounted to travel therein, of a rotatably 50 mounted member for each belt, an arm carried by each of said rotatable members, a belt pulley rotatably carried by each of said arms, a frame bar, a second arm carried by each of said members, bolts extending loosely 55 through said frame bar, springs interposed between said bolts and the ends of said second arms, adjusting nuts on said bolts on the underside of said frame bars, and supplemental springs interposed between said 60 nuts and said bars.

In testimony whereof I affix my signature in presence of two witnesses.

HARRY L. ROBY.
